BRUSH

Albert R. Racicot, Aurora, Ill., assignor to National Brush Company, Aurora, Ill., a corporation of Illinois

Application August 24, 1949, Serial No. 4,684

Term of patent 7 years

(Cl. D9—2)

To all whom it may concern:

Be it known that I, Albert R. Racicot, a citizen of the United States, residing at 419 Oak Park Avenue, Aurora, State of Illinois, have invented a new, original, and ornamental Design for a Brush, of which the following is a specification, reference being had to the accompanying drawing, forming a part thereof in which:

Fig. 1 is a perspective view of a brush, embodying my new design;

Fig. 2 is a side elevational view of the same;

Fig. 3 is an end elevational view thereof; and

Fig. 4 is a top plan view thereof.

I claim:

The ornamental design for a brush, substantially as shown.

ALBERT R. RACICOT.
